UNITED STATES PATENT OFFICE.

CHARLES F. BECKER, OF NEW PHILADELPHIA, OHIO, ASSIGNOR OF ONE-HALF TO
ROBERT A. ANDERSON, OF NEW PHILADELPHIA, OHIO.

SAFETY DEVICE.

1,129,269.

Specification of Letters Patent. Patented Feb. 23, 1915.

Application filed June 6, 1914. Serial No. 943,489.

To all whom it may concern:

Be it known that I, CHARLES F. BECKER, a citizen of the United States, residing at New Philadelphia, in the county of Tuscarawas and State of Ohio, have invented certain new and useful Improvements in Safety Devices, of which the following is a specification, reference being had to the accompanying drawings.

10 This invention relates to certain improvements in safety devices and has relation more particularly to a device of this general character especially designed and adapted for use in connection with punch presses or the like; and the object of the invention is to provide a device of this general character having novel and improved means whereby the hand of an operator in engagement with the work will be thrust to one side before the punching operation is effected.

15 The invention consists in the details of construction and in the combination and arrangement of the several parts whereby certain important advantages are attained and 20 the device is rendered simpler, less expensive and otherwise more convenient and advantageous for use, all as will be hereinafter more fully set forth.

25 The novel features of the invention will be 30 carefully defined in the appended claims.

In order that my invention may be the better understood, I will now proceed to describe the same with reference to the accompanying drawings, wherein—

35 Figure 1 is an elevational view of a press 40 punch with a safety appliance constructed in accordance with an embodiment of my invention applied thereto; Fig. 2 is an elevational view of the safety appliance as 45 illustrated in Fig. 1 but in a different adjustment, the coacting portions of the punch being indicated by dotted lines; and Fig. 3 is a view somewhat similar to Fig. 2 but showing the safety appliance in a still different adjustment.

50 As disclosed in the accompanying drawings, 1 denotes the bolster of a punch press of any ordinary or preferred construction, and 2 the reciprocating slide or head to 55 which the stamping punch or implement is adapted to be connected. Projecting forwardly of the head or slide to one side of the transverse center and substantially midway its length is the stud 3 to which is pivotally engaged the rock arm 4, the lower or free

extremity of which is disposed on a suitable curve, as indicated at 5, and adjustably engaged with the free extremity of such rock arm is the striking arm 6, herein disclosed as having its upper end portion provided with a longitudinal slot through which is directed the clamping means 7 carried by the rock arm and herein set forth as a conventional bolt and its coacting nut. The striking arm is adapted to be swung across the bolster 1 in close proximity thereto and serves to force the hand or arm of the operator, holding the work, to one side upon downward movement of the slide or head 2 so that the possibility of injury to the hand or arm of the operator during the punching operation is substantially entirely eliminated.

55 It will be observed that the connection between the striking arm 6 and the rock arm 4 permits an adjustment to meet the varying necessities of practice. I also find it of advantage in practice to have the engaging or free extremity of the striking arm 6, 60 inclosed within a rubber sleeve or cover 8, for 65 reasons which are believed to be self-evident. As herein disclosed, the requisite rocking movement is imparted to the rock arm 4 through the medium of the link 9 pivotally 70 engaged at one extremity to the rock arm 4 75 intermediate its length and at its opposite extremity to a stud 10 projecting forwardly from the head 11 of the press whereby it will be readily perceived that upon the reciprocation of the slide or head 2 the rock arm 4 80 will be caused to swing in front of the slide or head for the purposes desired. As herein disclosed, I have the link 9 comprised of a plurality of adjustably connected sections 85 12 for purposes which are believed to be 90 self-evident.

95 From the foregoing description, it is thought to be obvious that a safety device 100 constructed in accordance with my invention is of an extremely simple and comparatively inexpensive nature and is particularly well adapted for use by reason of the convenience and facility with which it may be assembled, and it will also be obvious that my invention 105 is susceptible of some change and modification without material departure from the principles and spirit thereof and for this reason I do not wish to be understood as limiting myself to the precise arrangement 110 and formation of the several parts herein.

shown in carrying out my invention in practice.

I claim:

1. The combination with a power operated press having a movable press head, of a safety device comprising an arm having its upper extremity pivotally engaged with the head to one side of the vertical center thereof, the lower extremity of the arm being offset in a direction toward the adjacent side of the head, a striking arm adjustably engaged with the offset portion of the arm, and means for positively oscillating said pivoted arm upon each stroke of the head.

2. The combination with a power operated press having a movable press head, of a safety device comprising an arm having its upper extremity pivotally engaged with the head to one side of the vertical center thereof, the lower extremity of the arm being offset in a direction toward the adjacent side of the head, a striking arm overlying the offset portion of the arm, said overlying portion of the striking arm being provided with an elongated longitudinally disposed slot, clamping means carried by the offset portion of the arm and disposed

through the slot of the striking arm to maintain the striking arm in its adjusted position, and means for positively oscillating said pivoted arm upon each stroke of the head.

3. The combination with a power operated press having a movable press head, of a safety device comprising an arm having its upper extremity pivotally engaged with the head to one side of the vertical center thereof, the lower extremity of the arm being offset in a direction toward the adjacent side of the head, a striking arm pivotally engaged with the offset portion of the arm, and a link pivotally engaged with the arm and with a stationary portion of the press above the head and at a side opposite to that to which the arm is attached, whereby said arm will be oscillated upon each stroke of the head, said link comprising a plurality of relatively adjustable sections.

In testimony whereof I hereunto affix my signature in the presence of two witnesses.

CHARLES F. BECKER.
